US00D811601S

(12) **United States Design Patent** (10) Patent No.: **US D811,601 S**
(45) Date of Patent: **** Feb. 27, 2018**

(54) **ADJUSTER FOR AIRWAY ESTABLISHMENT DEVICE**

(71) Applicants: **TAKASHIMA SANGYO CO., LTD.**, Nagano (JP); **KURUME UNIVERSITY**, Fukuoka (JP)

(72) Inventors: **Junji Oowa**, Chino (JP); **Jingo Kusukawa**, Kurume (JP); **Ryuichiro Tanoue**, Kurume (JP); **Kinuko Ogata**, Kurume (JP)

(73) Assignees: **Takashima Sangyo Co., Ltd.** (JP); **Kurume University** (JP)

(**) Term: **15 Years**

(21) Appl. No.: **35/500,931**

(22) Filed: **Nov. 12, 2015**

(80) **Hague Agreement Data**

Int. Filing Date: **Nov. 12, 2015**

Int. Reg. No.: **DM/088659**

Int. Reg. Date: **Nov. 12, 2015**

Int. Reg. Pub. Date: **May 13, 2016**

(51) **LOC (11) Cl.** 24-00
(52) **U.S. Cl.**

USPC **D24/181**

(57) **CLAIM**

The ornamental design for an adjuster for airway establishment device, as shown and described.

DESCRIPTION

1. Adjuster for airway establishment device

1.1 : Perspective

1.2 : Top

1.3 : Bottom

1.4 : Front

1.5 : Back

1.6 : Right

1.7 : Left
